UNITED STATES PATENT OFFICE.

LEON WILLIAMS, OF TOLEDO, OHIO.

RADIATOR.

1,055,434.

Specification of Letters Patent. Patented Mar. 11, 1913.

Application filed April 13, 1912. Serial No. 690,583.

To all whom it may concern:

Be it known that I, LEON WILLIAMS, a citizen of the United States, and a resident of Toledo, in the county of Lucas and State of Ohio, have invented a certain new and useful Radiator; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to radiators of the cellular type commonly used for cooling the water which is circulated around the cylinders of automobile engines, but is not restricted to such use as it may be employed 20 in any connection for which it may be adapted or appropriate.

The object of my invention is to simplify and improve upon the construction of radiators of this character, whereby to enhance the efficiency and practicability thereof, cheapen their cost of construction, and reduce to a minimum the liability of leakage.

A further object of my invention is to 30 build the radiator up from a plurality of units, any one of which can be easily removed for the purpose of repair or substitution without disturbing the other units.

The invention is fully described in the 35 following specification, and while, in its broader aspect, it is capable of embodiment in numerous forms, a preferred embodiment thereof is illustrated in the accompanying drawings, in which,—

Figure 1 is a front elevation of a radiator embodying my invention. Fig. 2 is an enlarged front edge view of three connected units thereof. Fig. 3 is a cross-section of such units on the line α , α in Fig. 2. Fig. 4 is an enlarged cross-section of one of the fin-carrying units. Fig. 5 is a plan of a blank of the outer member of a fin-carrying unit with a portion of the fins struck up, and Fig. 6 is a perspective view of the members of a fin-carrying unit partly removed.

Referring to the drawings, 1 designates the cellular structure of a radiator, and 2 the surrounding carrying frame therefor, which has its upper and lower portions 55 forming the customary receiving and dis-

pensing chambers of the radiator into which the respective ends of the radiator tubes or passages open.

The portion 1 of the radiator is composed of alternately arranged preferably 60 upstanding units a and b of sheet metal structure, the former of which forms merely water circulating passages of flattened or transversely elongated form, while the latter comprise the fin carrying units 65 of the radiator.

Each unit b comprises a flattened or transversely elongated water circulating member 3 which is preferably formed by flattening a sheet metal strip centrally upon 70 itself with its walls in spaced parallel relation and having its free edges lapping each other preferably at a vertical edge of the tube, as shown at 4 in Fig. 4, and soldered or otherwise suitably treated at such lap- 75 ping edge to seal the same against leakage. The side walls of the members 3 are continued at their ends beyond the vertical or front and back edges of the members to provide flanges 5, which are bent at right- 80 angles outwardly from the respective walls and are intended to lap and be soldered to the corresponding flanges 6 of the adjoining units a , which units are of the same construction as the parts 3 of the units b , 85 as best shown in Fig. 3. Each unit b also includes a fin-forming member 7, which is intended to transversely wrap around or encompass the part 3.

The fin-forming member 7 preferably 90 comprises a blank, which is provided at each side of its longitudinal center with a set of spaced parallel slits 8 extending outwardly from adjacent to said center and to near the associated outer edge of the sheet, substantially as shown in Fig. 5. The slits 8 of each set have short slits 9 extending in the same direction laterally from their ends to adjacent to the ends of the slits next in order, with the slits 9 at the same ends of the slits 8 preferably longitudinally alining. This manner of slitting the blank provides the center or longitudinal hinge-bar or strip 10, the outer parallel edge strips 11, 11, and the parallel transversely extending 95 bars or strips 12, which latter connect the center and outer strips 10 and 11 intermediate the ends of successive ones of the slits 9. The blank having been slotted in this manner, the fins 13, which are the parts 105 110

bounded by the slits 8 and 9, are bent outwardly in parallel outstanding relation, and the two halves or fin carrying portions of the blank are bent toward each other in opposition to the direction of projection of the fins.

In the assembling of the members of a unit *b*, a tube member 3 is inserted between the leaves or halves of a member 7, with one edge of the tube member in contact with the hinge-bar or strip 10 of the member 7. The leaves of the member 7 are then drawn in close parallel relation to the sides of the tube member, with one edge strip 11 thereof, which is broader than the other, bent around the outer edge of the member 3 and soldered or otherwise suitably secured in lapping relation to the outer side of the other strip 11 of the member 7, as shown at 14 in Fig. 4. It is thus apparent that each section or unit *b* comprises flat tube member 3 and an enveloping fin-forming member 7, whereas each unit *a* comprises a single flat tube member, which, in the present instance, is the same in construction as a member 3 of a unit *b*.

In the assembling of the radiator sections or units, a single unit *a* is disposed between units *b* of successive pairs so that the units *a, b* are arranged in alternate relation. The units are held in properly spaced relation by the fins 13 of the units *b*, such fins bearing at their outer edges against the adjacent side walls of the units *a* whereby to coöperate with such units and the sides of the tube members 3 of the units *b* in the forming of horizontally disposed air circulating cells between the units as shown. The units are held in such relation by a lapping and soldering of the adjacent unit flanges 5 and 6. When any desired number of units have been assembled in this manner the outer face thereof or that exposed in Fig. 2, is preferably dipped into a liquid solder to give the outer side of the radiator an integral appearance.

With this form of radiator it is a very simple matter to remove a section or unit for the purpose of repairing or substitution, as it is only necessary to break the soldered connection between the flanges 5 and 6 and the points at the face of the radiator where the sections may be soldered together in the dipping process, thus materially simplifying and quickening the repairing operation over the constructions of radiators commonly used. It will also be apparent with this construction of radiator that the possibility of leakage is reduced to a minimum, as the only seam in the water circulating tubes of the sections or units occurs at the point 4 thereof, or at the edge of the tube members where the edges of the sheets forming the same are lapped.

65 I wish it understood that my invention is

not limited to any specific construction or arrangement of the parts except in so far as such limitations are specified in the claims.

Having thus described my invention, what I claim as new, and desire to secure by Letters Patent, is,

1. In a radiator, a section comprising a water circulating member, and a rectangular sheet metal member enveloping a major portion of the circulating member, and having a plurality of section spacing fins projecting from each of opposite sides thereof. 75

2. In a radiator, a section having a water circulating member, and a single-piece rectangular sheet metal enveloping member having a plurality of laterally spaced air cell forming fins projecting outward therefrom at the sides of the water circulating member. 80

3. In a radiator, a section comprising a flat inner water circulating member, and a rectangular sheet-metal enveloping shell therefor, said shell having alternating openings and outwardly projecting tongues 90 which latter provide spaced cell forming fins at opposite sides of said member. 85

4. In a radiator, a section comprising a flat water circulating member and a rectangular encompassing member extending substantially from end to end of the circulating member and having portions projecting outwardly to form spaced parallel air cell forming fins at opposite sides of the circulating member, which fins are of greatest length from front to rear of the section. 95

5. In a radiator, a water circulating member which is substantially flat in cross section, an enveloping member extending transversely therearound with portions thereof on opposite sides of the circulating member provided with alternate openings and parallel fins, with the fins projecting outwardly from the sides of the circulating member and extending from front to rear of the radiator. 105

6. In a radiator, a plurality of adjoining water circulating sections, each alternate section having a member attached thereto and forming alternate openings and fins, 115 with the fins coöoperating with the adjacent water circulating sections to form air circulating cells which extend from front to rear of the radiator.

7. In a radiator, a plurality of adjoining water circulating sections, each alternate section having a metal enveloping jacket opposite sides of which are provided with alternate openings and fins, with the fins projecting outwardly from the respective 125 jacket sides and extending from front to rear of the section and forming air circulating cells between adjoining sections.

8. In a radiator, a plurality of spaced water circulating sections, each alternate 130

- section being provided with a sheet-metal enveloping member which is provided with alternate slots and tongues, the tongues comprising the metal which previously filled the 5 openings and projecting outwardly from the member in spaced parallel relation and co-operating with the sections to form air circulating cells therebetween, said tongues extending from front to rear of the radiator.
10. 9. In a radiator, a plurality of spaced up-standing water circulating members of flattened form in cross section, means rigidly connecting the upper and lower ends of adjoining sections, each alternate member having 15 a rectangular sheet-metal enveloping jacket with its opposite sides provided with alternate openings and outwardly projecting tongues which latter extend from front to rear of the radiator, said tongues abutting 20 at their outer edge against the respective sides of the adjoining sections and dividing the space between the sections into a plurality of transverse air circulating cells.
10. In a radiator, a section having a flat 25 vertically disposed water circulating tube and a sheet-metal member attached to and substantially covering a side of said tube, said member having spaced elongated slots, with the metal between said slots forming 30 a plurality of vertically spaced parallel bars, air cell forming fins attached to and projecting outward from said bars, said fins being of greatest length from front to rear of the radiator.
35. 11. In a radiator, a section comprising a flat water circulating tube and a sheet-metal member attached to each side of said tube and being substantially coextensive therewith, said members having vertically spaced 40 elongated openings forming intermediate bars in abutment with the respective sides of the tube, and air cell forming fins attached to and projecting outward from said bars in spaced parallel horizontal relation 45 and being of greatest length from front to rear of the radiator.
12. In a radiator, a section comprising a
- flat sheet-metal water circulating member having its end edges flanged outwardly, and a rectangular sheet-metal part enveloping 50 said member intermediate its flanges and being formed at each side of the member with vertically spaced parallel bars having air cell forming fins projecting horizontally therefrom, said bars and fins extending from 55 adjacent to the front edges to adjacent to the rear edges of the member sides.
13. In a radiator, a flat water circulating section, and a sheet-metal member wrapped around said section and being provided with 60 spaced openings forming edge and center bars longitudinally of said section, and vertically spaced parallel bars transversely of and connecting said edge and center bars, 65 said transverse bars having air cell forming fins projecting outwardly therefrom in spaced parallel relation, the center bar abutting against one edge of the section and the edge barslapping each other around the opposite edge of said section, substantially as 70 described.
14. In a radiator, a plurality of horizontally spaced flat water circulating sections, and a sheet-metal member enveloping each alternate section and having vertically 75 spaced transversely extending bars forming elongated openings therein from front to rear of the enveloped section and having fins projecting outwardly from said bars, to form air circulating spaces, said member also 80 having a longitudinally extending centrally disposed bar for abutting against one edge of the associated section, and longitudinally extending edge bars forlapping each other around the opposite edge of the section, 85 substantially as described.

In testimony whereof, I have hereunto signed my name to this specification in the presence of two subscribing witnesses.

LEON WILLIAMS.
